UNITED STATES PATENT OFFICE

HENRY W. ROOS, OF CINCINNATI, OHIO

APPARATUS FOR FORMING CONCRETE FLOORS

Application filed March 13, 1930. Serial No. 435,466.

This invention relates to improvements in apparatus for forming molds for concrete floors, and especially to that type of floor commonly known in the art as joist and tile construction. In this construction, forms are assembled to form continuous substantially parallel domes extending in one direction, with depressions between them for the formation of joists. These forms have been made of substantially uniform size and shape, with the result that it generally happens in assembling a floor that a space less than the length of the dome remains, which it is customary to fill by means of dome-shaped forms overlapping the ends of the adjacent dome forms in the assembled floor. The narrow space sometimes appears at the ends of the domes, and often results in the loss of much time in providing means for filling in or bridging the space.

The principal object of this invention is to provide simple and inexpensive means for filling this narrow space, and which can be quickly assembled in the floor mold.

Another object of the invention is to provide a dome-shaped form for a floor mold constructed of two parts relatively adjustable to form a short dome to fill in the narrow space.

A further object of the invention is to provide an adjustable dome-shaped form for a floor mold adapted to be mounted on an adjustable frame and adjustable as a unit with the frame to provide a short form adapted to be supported on temporary supports in the narrow space.

Still another object of the invention is to provide a frame for dome-shaped forms, which is longitudinally adjustable to the width of a narrow space in a floor mold.

A still further object of the invention is to provide a dome-shaped form constructed of two parts movable relatively to each other along the longitudinal dimension of the dome for adjustment, and means for securing the parts in adjusted position.

To these and other ends, the invention consists in the construction and arrangement of parts that will appear from the following description when read in conjunction with

the accompanying drawings, the novel features being pointed out in the claims following the specification.

In the drawings:

Fig. 1 is a fragmentary plan view of a floor mold assembled of dome-shaped forms, illustrating one application of this invention;

Fig. 2 is a vertical transverse section through an adjustable frame for a floor mold and showing an adjustable dome form mounted therein, the section being taken substantially on line 2-2 of Fig. 4;

Fig. 3 is a vertical longitudinal section through the adjustable dome form and its frame, taken substantially on line 3-3 of Fig. 2;

Fig. 4 is an enlarged inverted plan view of an adjustable frame showing an adjustable dome form mounted thereon, parts being broken away to conserve space, and

Fig. 5 is a section taken substantially on line 5-5 of Fig. 4, and looking in the direction of the arrow at said line.

Referring specifically to the drawings, in which like reference numerals refer to the same parts in all figures, 1 represents a unit form comprising a frame 2 having its corners cut away to fit around the tops 3 of temporary supports or shores on which the forms are mounted. Each of the frames is substantially rectangular in form and divided into two parts by means of a bar or bridge arranged between its ends, forming two parallel openings in each of which a dome-shaped form is mounted. A plurality of the frames 1 of substantially the same size and shape, and each having a pair of domes of uniform size and shape mounted thereon, are assembled on temporary supports in rows

extending both transversely and longitudinally of the floor to be formed to form a mold therefor. The dome-shaped forms are flush with the ends of the frames so that the ends of the dome forms on adjacent frames contact closely with each other and form in effect continuous parallel domes in the mold having depressions between them for the formation of joists.

When forms of uniform size and shape are

assembled in this manner to form a floor mold, it generally happens that a space remains between adjacent rows or at the end of the mold which is too narrow for the form 5 of standard size. In the embodiment illustrated herein, adjustable frames 5 having adjustable dome-shaped forms 6 mounted thereon are provided. These frames and domes are adjustable as a unit to fit the narrow 10 row space and are adapted to be assembled therein on the temporary supports.

Each of the frames 5 comprises a pair of end members 7, to the ends of which corner brackets 8 are secured by any suitable means, 15 such as welding. The brackets are angular in shape to fit around the tops of the shores which engage brackets on the shores to support the frames. The end members 7 are constructed of angular material having an inwardly projecting part 9 and a downwardly projecting flange 10 at the end of the frame. The brackets 8 are secured to the inner walls of the flanges 10 and are offset outwardly, flush with the outer walls thereof, 25 and extend outwardly toward the sides of the frame to a point flush with the end of the flange 9 which projects beyond the end of the flange 10. The bracket is then bent inwardly in a direction parallel with the sides of 30 the frame and then laterally toward the side of the frame at substantially right angles a distance substantially equal to the width of the side member of the frame and then at right angles in the direction in which said 35 side member extends.

Side rails generally referred to by the numeral 12 are arranged between the end members 7, and secured at their ends preferably by welding to the brackets 8. Arranged and 40 extending between the end members 7 of the frame is a cross-bar or bridge. The bridge 13 is arranged substantially parallel to the side bars 12 and midway between them, thus dividing the frame into two parts of substantially the same size and shape. Upon reference to Fig. 4 it will be noted that the bridge 13 is of substantially twice the width of the side member 12.

The side members 12 and the bridge 13 are each constructed in two parts movable toward and from each other for purposes of adjustment to vary the length of the frame. To this end, the side members of the part 15 of the frame each comprise an angle iron having a horizontal portion 16 and a downwardly projecting flange 17 at its inner side. These side members are of a length substantially equal to one-half the length of the frame when fully extended. Secured to the lower wall of the horizontal portion 16, preferably by welding, are a plurality of brackets 18 spaced from each other and having downwardly projecting flanges adjacent the outer side of the side member of the frame. Only two of these brackets are shown

in the drawings; however, it will be understood that a greater number may be employed, if required.

The other part 20 of the frame also has side members each comprising a horizontal part 21 and a downwardly projecting flange 22 at its inner edge, and a plurality of brackets 23, in all respects like the brackets 18, are secured to the undersurface of the part 21. Secured to the brackets 23 or the downwardly projecting flanges, preferably by means of bolts as shown, is a longitudinally arranged rod or bar 24 which projects inwardly beyond the inner ends of the flanges 21, and at its inner end is provided with a plurality of slots or openings 24' adapted to register with openings in the downwardly projecting flanges of the brackets 18, whereby they may be secured thereto by means of bolts arranged in the openings.

Secured to the outer side of the flange 22, by means of bolts or other suitable means, is a second rod or bar 25 parallel with and of substantially the same length as the bar 24. The bar 25 is also provided with slots or openings adjacent its inner end which correspond with the openings in the bar 24. The inner end of the bar 25 overlaps the outer face of the downwardly projecting flange 17, which is provided with openings with which the openings in the bar 25 are adapted to register for the reception of bolts, whereby the bar may be secured to the flange.

The cross-bar or bridge is also constructed of two parts movable relatively to each other for purposes of adjustment. Secured to the end member of the part 15 are a pair of angle irons 27 spaced from each other and substantially parallel, see Fig. 2. Each of these irons has a downwardly projecting flange 28 at its outer edge and an inwardly projecting flange 29 at its upper edge. A cover in the form of a sheet metal plate 30 may be supported on the flanges 29 to bridge the space between them. A similar pair of angle irons 31 are secured to the end member of the part 20, and are of a length substantially equal to the length of the corresponding angle irons in its sides. The space between the angle irons 31 is also bridged by means of a plate 32 of sheet material.

A rod or bar 33 is secured to the inner faces of each of the flanges 28 by means of bolts, as shown, or other suitable means. The rods 33 are arranged substantially parallel with each other and with the bars 24 and 25 in the sides of the frame, and of substantially the same length. The inner ends of the rods 33 are also provided with openings or slots adapted to register with openings in the flanges 28 for the reception of bolts, whereby the rods 33 are secured thereto. It will be understood that by removing the bolts which secure the flanges 28 and 17 and the brackets 18 to the rods 24, 25 and 33, the two parts 15

and 20 of the frame are free to be moved or adjusted toward or from each other and the bolts may then be reinserted in the newly aligned openings for securing or retaining the 5 parts in the adjusted position.

Adjustable dome-shaped forms are provided which are adapted to be mounted in the frame, one in each of the openings therein. Each of said dome forms comprises two 10 parts 35 and 36, preferably constructed of sheet material and having a substantially horizontal top portion 37 from which the sides incline outwardly and downwardly at 38, and then downwardly at 39 at substantially 15 right angles to the top. The part 36 is adapted to be secured in the part 15 of the frame, and for this purpose the lower vertical portions of its sides are provided with openings adapted to register with openings in the flanges 17 and 28 and also with the openings in the bars 25 and 33, so that it may be secured thereto by the same bolts which secure the parts of the frame in adjusted position. The part 36 is mounted on 20 the other end of the frame and is provided with openings adapted to register with the openings in the bars 33 and 25 so that it may also be secured to the frame by the same bolts which secure said bars to the bridge 25 and side members. The part 35 of the dome form overlaps the part 36 and may be constructed of a slightly larger size to allow for the thickness of the material.

The part 36 of the dome is secured in the part 20 of the frame as previously described, and the part 35 is then arranged over the part 36 of the dome and on the other end of the frame, with its inner end overlapping the inner end of the part 36 a distance depending on the adjustment of the frame or the width of the narrow space. The bolts for securing the dome to the part 15 of the frame, and the part of the frame to the rods 33 and 25 are then inserted for securing the 45 parts together.

At the ends of the frame, the sides of the dome forms are cut out to provide a clearance for the ends of the frame so that the ends of the dome forms may project thereover to be flush with the end of the frame. By this arrangement, the ends of the domes fit closely against the ends of the domes on the adjacent frames to continue the same as a unit over the narrow space. 50 By this construction, the domes are adjusted with the parts of the frame to fit the narrow space, and secured in the adjusted position by securing the rods 24 and 25 to the part 15.

Reinforcing strips 40 in the form of angles 55 may be secured to the inner walls of the dome at suitable intervals to prevent sagging or bending of the material under a heavy load of concrete. One such reinforcing strip is provided in the inner end of

the part 36, but they are omitted from the inner end of the part 35 for such a distance as it may overlap the inner end of the part 36 in its various positions of adjustment.

Upon reference to the drawings, it will be 70 noted that open spaces 45 are formed in the sides between the inner ends of the parts 16 and 21 and also between the corresponding parts of the bridge. These openings are readily filled by means of strips of sheet 75 material of a width substantially equal to the width of the bridge member or twice the width of the side members of the frame, and of a length sufficient to overlie the inner ends of the side and bridge members. 80

In Fig. 1, the floor is shown framing into a beam at the left. The beam forms are suspended from T-shaped forms 46, cut out at their ends to fit around the tops of the shores 3 on which they are supported. The 85 ends of the domes adjacent the beam are open, and means are provided for closing the open ends of the domes along the sides of the beam. Said means comprises an end plate 47 shaped to conform substantially to 90 the cross-section or end of the dome and adapted to engage the end of the dome or a reinforcing strip 40 therein. At its lower edge, the end plate has an inwardly projecting flange 48 adapted to engage the top of 95 the end of the frame to which it may be secured by bolts or other suitable means.

Although the invention has been described with reference to a single embodiment thereof, it will be understood that this application is intended to cover such changes or modifications thereof as may come within the spirit of the invention or scope of the following claims.

I claim:

1. A unit form for concrete floor molds comprising a substantially rectangular frame having a pair of openings therein and comprising two parts adjustable relatively to each other, a bridge extending longitudinally of said frame and separating said openings, a plurality of rods projecting inwardly from one of said parts each having a plurality of openings therein, a plurality of flanges on the sides and bridge of the other of said parts overlapping said rods and each provided with a plurality of openings arranged to register with corresponding openings in said rods, means detachably arranged in said openings for securing the flanges to the rods and the parts of the frame to each other, a dome form mounted in each of said openings in the frame, and means on the frame engageable directly with shores on which it is mounted.

2. A unit form for concrete floor molds comprising a substantially rectangular frame having a pair of openings therein and cut away at its corners to engage the sides of shore tops in the plane of which the frame is 130

adapted to be mounted, said frame comprising side and end members and a bridge connecting said end members and separating the openings of said pair, each of said side members and bridge comprising two parts, a downwardly projecting flange on the outer side of each part of said side members, a plurality of brackets on the side members of one of said parts having downwardly projecting flanges spaced inwardly from said first mentioned flanges, bars secured to and between the flanges on said brackets and side member and projecting therefrom to overlap and engage the flanges on the side members of the other part of the frame, and means for securing said bars to said flanges on the other part for retaining the parts of the frame in adjusted position.

In witness whereof, I have hereunto signed
20 my name.

HENRY W. ROOS.
